UNITED STATES PATENT OFFICE.

JOHN E. ROHRBECK, OF WEST HOBOKEN, NEW JERSEY.

DESIGN FOR A MIRROR-PLATEAU.

44,113.

Specification for Design.

Patented May 27, 1913.

Application filed March 3, 1913. Serial No. 751,933. Term of patent 3½ years.

To all whom it may concern:

Be it known that I, JOHN E. ROHRBECK, a citizen of the United States, residing in West Hoboken, Hudson county, New Jersey, have invented a new, original, and ornamental Design for a Mirror-Plateau, of which the following is a specification, reference being had to the accompanying drawing, forming part thereof.

The design in plan view is of generally octagonal form, as shown in Figure 1. The octagonal plane is of palpable thickness, and is so shown in side view in Fig. 2. The so-existent plate has eight corners, four of which are unimpeded in approach. The said four are alternate corners. At each of the intervening alternate four corners is a downwardly-extending foot supported as by scrolls against the edge of the plate at each side of the relevant corner.

Fig. 2 shows at the middle of the figure such foot in elevation. At the sides of said figure are shown the feet of the next alternate corners, viewed isometrically from the point of view of the first-named foot. Between the feet is shown the intervening edge of the plate. The view is similar from the like point of view opposite each of the four feet.

I claim:

The ornamental design for a mirror plateau, as shown.

In testimony, that I claim the foregoing as my invention, I have signed my name in presence of two subscribing witnesses.

JOHN E. ROHRBECK.

Witnesses:

GUSTAV T. ROHRBECK,
CHAS. E. ROHRBECK.
